Primary Examiner — Derrick Holland*Assistant Examiner* — Jennifer O King(74) *Attorney, Agent, or Firm* — Miller Thompson LLP; Tai W. Nahm(57) **CLAIM**

The ornamental design for an angle hood, as shown and described.

DESCRIPTION

FIG. 1 illustrates a top, front, left perspective view of an angle hood in accordance with the new design.

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown represent unclaimed subject matter and form no part of the claimed design.

1 Claim, 4 Drawing Sheets(56)
